[57] CLAIM

The ornamental design for a baby rocker, substantially as shown and described.

DESCRIPTION

FIG. 1 is a front perspective view of a baby rocker showing my design;

FIG. 2 is a left side elevation view of the rocker;

FIG. 3 is a right side elevation view of the rocker;

FIG. 4 is a front elevation view of the rocker;

FIG. 5 is a top plan view of the rocker;

FIG. 6 is a bottom plan view of the rocker;

FIG. 7 is a rear elevation view of the rocker; and

FIG. 8 is a right front perspective view of the rocker, without the sun hood and with the rocker stops in an alternative position.

FIG. 1

FIG. 2

FIG. 3

FIG. 4

FIG. 5

FIG. 6

FIG. 7

FIG. 8
